JUG

Roy W. Dike, Northbrook, Ill., assignor to The Climalene Company, Canton, Ohio, a corporation of Ohio

Filed Aug. 10, 1964, Ser. No. 81,212

Term of patent 14 years

(Cl. D58—5)

Fig. 1

Fig. 2

Fig. 3

Fig. 4

Fig. 5

FIGURE 1 is a side elevation of a jug, showing my new design;

FIG. 2 is a rear elevation thereof;

FIG. 3 is a top plan view thereof;

FIG. 4 is a top front perspective view thereof on a reduced scale; and

FIG. 5 is a rear perspective view thereof.

I claim:

The ornamental design for a jug, substantially as shown.
